UNITED STATES PATENT OFFICE

2,609,671

AIR FLUE IN REFRIGERATING APPARATUS

Thomas C. Gleason, Detroit, Mich., assignor to
Chrysler Corporation, Highland Park, Mich., a
corporation of Delaware

Application June 30, 1950, Serial No. 171,451

2 Claims. (Cl. 62—117.4)

1

This invention relates to means for augmenting a draft of air over a static condenser.

In refrigeration systems of the type employing a compressor, a condenser and an evaporator it is common practice to use a blower or fan to create a draft of air over the condenser to cool the refrigerant therein. However, in many installations the problem of servicing the fan or blower is objectionable and the cost of such a blower or fan is an item which it is desirable to eliminate. When the blower or fan is eliminated and the natural flow of air through a stack is utilized to cool a condenser, usually referred to as a static condenser, the coil area of the condenser must be increased to make up for the poor air flow and a larger condenser is both expensive and space consuming.

It is a principal object of this invention to provide means to augment the flow of air over a static condenser by the use of a simple heating device which increases the stack effect and thereby makes possible the use of a condenser coil of smaller size than that which would normally be required where a natural draft of air is relied upon for condenser cooling.

In the drawings:

Fig. 1 is an elevational view partly broken away of the back portion of an ice cream cabinet embodying my invention; and

Fig. 2 is a section taken on the line 2—2 of Fig. 1.

In the drawings an ice cream cabinet of the type commonly used in drug stores, soda fountains and grocery stores and which has a height which is substantially waist high has been designated by the numeral 10. The cabinet 10 includes a compartment 12 in which material to be cooled such as ice cream may be kept and which has an evaporator coil 14 mounted therein. The evaporator coil 14 has its outlet end connected by a pipe 15 to a compressor 16 preferably driven by an electric motor 18 and the compressor discharges compressed refrigerant through a tube 20 to a condenser 22. The condenser 22 discharges cooled compressed refrigerant to a receiver 24 which is connected by tube 26 to a conventional expansion valve 28 which in turn is connected by tube 30 to the inlet of the evaporator 14 thus completing a refrigerant circuit.

The cabinet 10 is preferably constructed so that a partition means 32 defines a duct 34 which extends along a portion of the bottom of the cabinet 10 and has an air inlet opening 36. The duct 34 adjacent the rear of the cabinet 10 extends upwardly to form a stack 38 having an air

2

outlet opening 40. The condenser 22 is mounted within the duct 34 as illustrated in Fig. 2 so that air entering opening 36 and travelling through duct 34 and stack 38 and discharged through opening 40 tends to dissipate heat from the condenser 22. The natural stack effect of the stack 38 tends to produce a limited circulation of air through the duct 34 and stack 38, but as explained above this circulation of air is generally inadequate.

In order to augment the circulation of air through the duct 34 and stack 38 I mount an electric resistance heater 42 which is preferably in the shape of an elongated strip extending 15 transversely of the stack 38 downstream of the condenser 22 so that when electric current is passed through the heater 42 the air in stack 38 is heated so that it rises and increases the flow of air over the condenser 22. The heater 42 is 20 positioned so that its thinnest dimension is presented to the airstream so that it will offer a minimum obstruction to the flow of air in stack 38.

If desired the resistance heater 42 may be 25 wired so that it is energized electrically whenever the compressor motor 18 is energized. A diagrammatic wiring arrangement is illustrated in Fig. 1 which shows a conductor 50 connected to a source of electric energy and a control device such as a thermostatic switch 52 adapted to close when the temperature within compartment 12 exceeds a predetermined value. A conductor 54 may be connected to the switch 52 and to an inlet terminal of the motor 18 and an inlet terminal of the heater 42. The outlet terminals of the motor 18 and heater 42 are connected by conductors 58 and 60, respectively, to a conductor 56 which is connected to the source of electric energy. This control is illustrated as one application of the invention to show that it would not be necessary for the heater to be energized constantly.

I claim:

1. A refrigerated cabinet for foodstuffs having a height which is substantially waist high, said cabinet having a compartment for the reception of foodstuffs to be cooled and a mechanical refrigeration system of the compressor-condenser and evaporator type operable to cool said compartment, said cabinet including means defining a vertically extending stack operable to establish a passage for air and means defining an air inlet to the lower portion of said stack and an air outlet adjacent the top of said stack, an air cooled condenser which forms an operating com-

ponent of said refrigeration system positioned in the lower portion of said stack and an electric resistance heater positioned in said stack downstream of said condenser to improve the draft in said stack.

2. A refrigerated cabinet for foodstuffs having a height which is substantially waist high, said cabinet having a compartment for the reception of foodstuffs to be cooled and a mechanical refrigeration system including an evaporator for cooling said compartment, a compressor driven by an electric motor and a condenser coil of the air cooled type for dissipating heat, said cabinet including means defining a vertically extending stack operable to establish a passage for air and means defining an air inlet to the lower portion of said stack and an air outlet adjacent the top of said stack, said condenser coil being mounted in the lower portion of said stack, an electric re-

sistance heater positioned in said stack downstream of said condenser to improve the draft in said stack and control means to energize said heater and said electric motor simultaneously.
